US00D597079S

(12) **United States Design Patent**
Andre et al.

(10) **Patent No.:** **US D597,079 S**
(45) **Date of Patent:** **** Jul. 28, 2009**

(54) **DOCK INSERT**

(75) Inventors: **Bartley K. Andre**, Menlo Park, CA (US); **Peter Russell-Clarke**, San Francisco, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Vincent Keane Seid**, legal representative, Los Gatos, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/319,055**

(22) Filed: **Jun. 3, 2008**

CLAIM

The ornamental design for a dock insert, as shown and described.

DESCRIPTION

FIG. 1 is a front perspective view of a dock insert showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another front perspective view thereof, showing the design in an environment of use;

FIG. 9 is another perspective view thereof;

FIG. 10 is a front view thereof, showing the design in an environment of use with an electronic device; and,

FIG. 11 is a side view thereof.

The broken lines in the Figures are for illustrative purposes only and form no part of the claimed design.
